UNITED STATES PATENT OFFICE.

ORESTES U. BEAN, OF NEW YORK, N. Y., ASSIGNOR TO BUNSEN SMOKELESS FURNACE COMPANY OF AMERICA, A CORPORATION OF SOUTH DAKOTA.

BOILER-FURNACE.

No. 897,446.

Specification of Letters Patent.

Patented Sept. 1, 1908.

Application filed August 29, 1907. Serial No. 890,631.

To all whom it may concern:

Be it known that I, ORESTES U. BEAN, citizen of the United States, residing at New York, in the county of New York and State of New York, have invented certain new and useful Improvements in Boiler-Furnaces, of which the following is a specification.

My invention relates to certain new and useful improvements in boiler furnaces, and the object of my invention is to produce a furnace in which practically complete and perfect combustion of the fuel is obtained, whereby the smoke is eliminated and great economy in fuel consumption is effected.

A further object of my invention is to produce a furnace which is simple and durable in construction, and one in which the life of the boilers is prolonged by the more nearly equal distribution of the heat to all parts of the boiler sheets and tubes.

With these and other objects in view my invention consists in certain constructions, combinations and arrangements of parts, the preferred form of which will be first described in connection with the accompanying drawings and then the invention particularly pointed out in the claims.

Referring to the drawings wherein I show one form of my invention and wherein the same part is designated by the same reference numeral wherever it occurs, Figure 1 is a central longitudinal section of a furnace embodying my invention, the boiler being shown in elevation; Fig. 2 is a horizontal section of the furnace taken on line 2, 2 of Fig. 1; Fig. 3 is a transverse section taken on line 3, 3 of Fig. 1.

1 is the fire-box provided with horizontal grate sections 2, below which is the ash pit 3. On the sides of the horizontal grate sections 2 I provide inclined supplemental grate sections 4. These inclined grate sections preferably extend up to about the height of the fire carried on the grates, and thereby admit an increased amount of air to the fire.

5 is a bridge wall of ordinary construction which likewise extends up to the normal height of the fire. On top of the bridge wall 5 I provide a series of piers 7, preferably triangular in cross-section, the points of the triangles facing the fire box. These triangular piers extend up to the refractory cover 8, which preferably extends between the top 55 of the furnace and the tubes in the boiler.

These piers form a series of openings 9, the aggregate area of which should correspond to the area of the uptake of the boiler. These openings 9 operate by their form to intimately intermingle the carbon and oxygen remaining unmixed after primary combustion in the fire box is completed. This produces a chemical union between the carbon and oxygen and produces further combustion in the portion of the furnace 65 beyond these piers.

To the rear of the bridge wall 5 I provide a series of piers 10 which, preferably, and as shown are rectangular in cross section, these piers being located in line with the openings 70 9 between the piers 7. These piers deflect the streams of mixed gases passing through the openings 9, and further mix the same, thus assisting the combustion. These piers preferably, and as shown, do not extend up to 75 the refractory cover 8, but a space is left over the tops of these piers as best shown in Fig. 1.

To the rear of the piers 10, I build up tight against the refractory cover 8 a second bridge wall 11, through which I provide a series of 80 openings 12, in line with the openings 9, and consequently behind the piers 10. Preferably, and as shown, these openings are of dove-tail form in cross section, with their smaller ends facing the piers 10. The cross sectional 85 area of these openings preferably corresponds to the cross sectional area of the openings 9. From this construction it will be seen that between the bridge walls 5 and 11 a second combustion or regenerative chamber 13 is formed 90 in which the complete combustion of all gases passing out of the fire box is effected. In order to supply air to properly support the combustion in this second chamber 13, I provide an air passage 14 in the bridge wall 5, 95 said passages leading from the ash pit 3.

15 denotes a damper by means of which the supply of air to the passages 14 is controlled. This damper may be operated in any suitable manner, as for instance by 100 means of the lever 16 indicated at the side of the furnace.

18 designates air passages extending from the passages 14 in the bridge wall 5, to the upper portion of the piers 10, and 19 designates twyers extending from the sides of the piers 7 and into the openings 9, said twyers being connected with the air passages or ducts 14, whereby air is mixed with the gases as they pass through the openings 9. 110

20 designates twyers mounted in the top of the piers 10 and connected to the passages 18 in the piers 10, whereby further air is supplied in the chamber 13.

5 By the construction above described it will be seen that the unconsumed gases passing out of the fire box will be thoroughly mixed together, and more air added in their passage into and through the secondary chamber 13, and that for this reason the combustion will be practically complete. In addition to this, because of the inclined grate sections in the sides of the main grate a larger amount of air will be fed to the fire 15 on the grates than would be the case were only flat grate sections used.

While I have described what I believe to be the preferred form of my invention, I desire to have it understood that many changes 20 may be made in the form, construction and arrangement of parts without departing from the spirit of my invention.

What I claim as new and desire to secure by Letters Patent is:

25 1. In a boiler furnace the combination with a fire box, of a bridge wall in the rear of said fire box, a combustion chamber in the rear of said bridge wall, a series of piers separated from each other mounted on top of the bridge wall and extending from the top of the bridge wall to the lower surface of the boiler, whereby a plurality of restricted openings 30 are formed for the passage of the products of combustion, a second series of piers located adjacent to the bridge wall and extending from the bottom of the combustion chamber to a height less than the height of the top of the first mentioned piers and in line with the restricted openings between the first series of 35 piers, said bridge wall being provided with an air chamber, and both of said series of piers being provided with air channels having suitable outlets and connected to the air chamber in the bridge wall.

40 2. In a boiler furnace the combination with a fire box, of a bridge wall in the rear of said fire box, a combustion chamber in the rear of said bridge wall, a series of piers separated from each other mounted on top of the bridge wall and extending from the top of the bridge wall to the lower surface of the boiler, whereby a plurality of restricted openings 45 are formed for the passage of the products of combustion, a second series of piers located adjacent to the bridge wall and extending from the bottom of the combustion chamber to a height less than the height of the top of the first mentioned piers and in line with the restricted openings between the first series of 50 piers, said bridge wall being provided with an air chamber, both of said series of piers being provided with air channels having suitable outlets and connected to the air chamber in the bridge wall, said bridge wall being provided with an opening from the ash-pit into

the air chamber by which air is supplied to the chamber, and a damper having its operating part extending outside the furnace to control the supply of air.

3. In a boiler furnace the combination 70 with a fire box, of a bridge wall in the rear of said fire box, a combustion chamber in the rear of said bridge wall, a series of piers separated from each other mounted on top of the bridge wall and extending from the top of the bridge wall to the lower surface of the boiler, whereby a plurality of restricted openings 75 are formed for the passage of the products of combustion, a second series of piers located adjacent to the bridge wall and extending from the bottom of the combustion chamber to a height less than the height of the top of the first mentioned piers and in line with the restricted openings between the first series of piers, said bridge wall being provided with an 80 air chamber, and both of said series of piers being provided with air channels having suitable outlets, the outlets in the first mentioned piers being located on the sides thereof, and the outlets on the second mentioned piers 85 being located in the top thereof and connected to the air chamber in the bridge wall.

4. In a boiler furnace the combination with the fire box, of a bridge wall to the rear 90 of said fire box, a series of piers separated from each other mounted on top of the bridge wall and extending from the top of the bridge wall to the lower surface of the boiler whereby restricted openings are formed for the 95 passage of the products of combustion, a second series of piers located adjacent to the bridge wall and in line with the restricted openings, a second bridge wall to the rear of said last mentioned piers, said bridge wall having a series of restricted openings there-through 100 in line with said last mentioned piers.

5. In a boiler furnace the combination with a fire box, of a bridge wall in the rear 105 of said fire box, a combustion chamber in the rear of said bridge wall, a series of polygonal piers separated from each other mounted on top of the bridge wall and extending from the top of the bridge wall to the lower surface of the boiler, whereby a plurality of restricted 110 openings are formed for the passage of the products of combustion, a second series of polygonal piers located adjacent to the bridge wall and extending from the bottom of the combustion chamber to a height less 115 than the height of the top of the first mentioned piers and in line with the restricted openings between the first series of piers, said bridge wall being provided with an air chamber, and both of said series of piers 120 being provided with air channels having suitable outlets and connected to the air chamber in the bridge wall.

6. In a boiler furnace the combination with a fire box, of a bridge wall in the rear of 130

said fire box, a combustion chamber in the rear of said bridge wall, a series of polygonal piers separated from each other mounted on top of the bridge wall and extending from 5 the top of the bridge wall to the lower surface of the boiler, whereby a plurality of restricted openings are formed for the passage of the products of combustion, a second series of polygonal piers located adjacent to the 10 bridge wall and extending from the bottom of the combustion chamber to a height less than the height of the top of the first mentioned piers and in line with the restricted openings between the first series of piers, said 15 bridge wall being provided with an air chamber, both of said series of piers being provided with air channels having suitable outlets, the outlets in the first mentioned piers being located on the sides thereof and the 20 outlets on the second mentioned piers being located in the top thereof and connected to the air chamber in the bridge wall.

7. In a boiler furnace the combination with the fire box, of a bridge wall to the rear

of said fire box, a series of piers separated 25 from each other mounted on top of the bridge wall and extending from the top of the bridge wall to the lower surface of the boiler whereby restricted openings are formed for the passage of the products of combustion, a series of piers to the rear of and adjacent to said bridge wall and in line with the restricted openings, a second bridge wall to the rear of said last mentioned piers, said bridge wall having a series of restricted openings therethrough in line with said last mentioned piers, said bridge wall being provided with an air chamber, and both of said series 30 of piers being provided with air channels having suitable outlets and connected to the 35 air chamber in the bridge wall.

In testimony whereof I affix my signature in presence of two witnesses.

ORESTES U. BEAN.
